UNITED STATES PATENT OFFICE

2,135,177

MARGIN-REGULATING STOP

Harold C. Fox, Waterloo, Iowa

Application July 1, 1937, Serial No. 151,384

REISSUED

4 Claims. (Cl. 197—63)

My invention relates to improvements in margin-regulating stops for typewriting machines or the like apparatus, and it is an object of my improvements to provide simply constructed inexpensive means therefor adapted for convenient single hand manual actuation of such stops in practice.

Another object of my improvements is to include with the margin regulating means resiliently controlled flexible connecting means for the stops for coaction with manually controlled selective means for releasing severally the stops in relation with a medial fixed abutment for coaction therewith.

Another object of my improvements is to include in the above train of mechanically cooperating devices a single tensioning means for actuating the stops singly as desired when said manually selective means is used appropriately 20 in the unlocking of either from a shiftable dentated carrier bar on which they are slidably mounted, to accomplish the desired adjustments of either stop as stated.

I have accomplished the above objects by the 25 means and mechanisms which are illustrated in the accompanying drawing, described in the specification and claimed in the appended claims.

It is to be understood that various changes may 30 be effected in the different devices of my invention and their relative positions, without thereby departing from my invention and the scope of the claims.

Figure 1 is a perspective frontal view of my 35 invention, as mounted upon spaced side arms of a typewriting machine. Fig. 2 is a top plan of parts of the dentated cross-bar and the pair of stops slidably connected thereto with other and associated elements, other parts being broken away. Figs. 3 and 4 are respectively transverse 40 sections of the cross-bar, the said stops mounted thereon, and the manually operable rock-bar for operating the release mechanism of either stop. Fig. 5 is a medial longitudinal vertical section of the stop shown in Fig. 3, and Fig. 6 is a transverse section of the cross-bar and the stop of Fig. 3, showing the ratchet part of the release 45 stem device disengaged from the teeth of the cross-bar.

Fig. 1 is a perspective view of portions of the 50 shiftable carriage of a typewriting machine, showing my improved marginal stops releasably secured on a transverse dentated bar thereof, and connected for resilient actuation according to my invention, parts of the carriage frame being broken away, or other parts not shown. Fig. 2 is a top plan, with parts broken away, showing the relative associations between the shiftable marginal stops on the dentated bar, relative to a medially positioned relatively fixed abutment and 55 to a flexible operative connection between the

stops. Figs. 3 and 4 are respectively medial cross sections of the two marginal stops, and also showing the associated manually operable releasing means therefor.

I have shown in Fig. 1 a portion of the shiftable carriage 1 of a typewriting machine, including vertically disposed end supports connected by a cross-bar 5 whose lower edge has a row of detents 5a. On the bar 5 are slidably mounted a pair of marginal stops 9 and 10 respectively. In Fig. 2 is shown to the rear of the bar 5 a conventional fixed abutment device 11b on a backing part 11 of the machine. There are two abutment devices 11b and 11c, the first relatively fixed, and the other being a rockable stop finger 11c having an eccentrically disposed lateral screw 11f to be stopped in one direction by the member 11a, and in an opposite direction by a finger part 11d engageable with the part 11a.

Referring to Figs. 3 to 6 inclusive, Figs 3 and 4 are transverse sections of the cross-bar 5 with the stops 9 and 10 thereof respectively mounted thereon and in detent engagement therewith. The element 5 appears in both, while the elements 9, 9a, 9b, 9c, 9d, of Fig. 3, are the same as 25 the similar elements 10, 10a, 10b, 10c and 10d of Fig. 4. In Fig. 2 are shown the rearward projections 9e of the stop 9, and the rearward projections 10e and 10f of the stop 10. Figs. 5 and 6 further illustrate the features of the stop 9, Fig. 5 30 showing the detent 9f in its position separated from the cross-bar 5 but as in a position of the detent as when engaged therewith, while in Fig. 6 the rock-bar 2 is shown as operatively engaged with the cap projection 9b, and as having pushed 35 down the detents 9f releasing the stop from the cross-bar 5 to permit sliding of the stop on the cross-bar. In Fig. 6, the cap 9c is depressed by the rock-bar 2 engaging and pushing downwardly on the stud 9d. The cap is integral with a 40 depending stem 9a cylindrical at the top and excised lengthwise below with a flat forward face and having at its lower end a forwardly projecting pair of ratchets 9f adapted to engage in fitting notches of the stop 9. A coiled spring 9b 45 is seated within the cap 9c around the cylindric part of the stem 9a, and is engaged with the top of the stop 9, and when compressed as in Fig. 6 and then released, the spring reacts to return the stem 9a to reengage the ratchets with teeth of 50 the cross-bar 5.

Fig. 4 is a section of the other stop 10, and the above description of the stop 9 and its parts applies also to the like parts of the stop 10, viz.; as shown at 10a, 10b, 10c, and 10d, excepting the 55 use on the stop 10 of a rearwardly obliquely projecting member 10e, which may be stopped by the rockable abutment member 11c. The stop 10 also has a rearwardly projecting beveled member 10f used as a bell ringer, as in common practice. 60

A sheave 15 is rotatably mounted upon the left-hand side standard of the frame 1. Another sheave 14 is rotatably mounted upon the left-hand part of the forward face of the stop 5. 10. A spring drum 7 is rotatably mounted upon a headed screw 6 which is threaded into said left-hand standard. The drum 7 contains a spiral spring 8 whose inner end is secured to the shank of the screw 6, while its outer end is fastened by a rivet 8a to the inner circumferential wall of the drum. A flexible non-extensible cord or cable 12 has one termination secured by a screw 13 to the forward wall of the stop 9 below its division, and is carried to the right-hand to and around the grooved edge of the sheave 14 reversely to the left-hand, thence around the grooved sheave 15 upwardly and to wind upon the circumferential periphery of the drum 7 to which it is end-attached. The spring 8 may be placed under tension by turning the screw axis appropriately, thus placing the cable 12 under lengthwise tension.

A rockable rod 3, of widened or elliptical cross section, has end pintles 2 rockably seated through the side standards of the frame 1, the right-hand pintle having a short crank-handle 4 for manual use. The rod 3 is immediately above the upper edge of the dentated bar 5 in spaced relation and parallel therewith, but normally as shown clearing the offset projections 9d and 10d of the vertically movable heads 9c and 10c on the stops 9 and 10. In this position of the rod 3, as shown in Figs. 3 and 4, the heads 9c and 10c of said stops are cleared, and the springs 9b and 35 10b which press upon the caps 9c and 10c, respectively retain the stops 9 and 10 in upper positions with the stop detents 9f engaged with the bar detents 5a.

When by means of the crank handle 4 the rod 3 is rocked forwardly downwardly, (see Fig. 40 3), its near edge part presses down the projection 9d and cap 9c, compressing the spring 9b, and by this spring pushing down the ratchet 9f, thus releasing the lower cross part of this stop 45 from the detents of the bar 5.

The released stop 9 may then be slid along the bar 5 to a desired marginal position, and the crank 4 being released, the spring 9b reacts as the rod 3 is rocked to its medial position, the head 50 9c returning with the stop frame 9 to re-lock it to the bar 5. The spring 8 in the barrel 7 acts in tensioning the cord 12 and stop 9 to move the stop to the right. The stop may be returned slidably when the crank is rocked forwardly. The 55 other stop 10 is controlled in the same manner by rocking the rod 3 rearwardly instead of forwardly, acting to depress the oppositely offset projection 10d of the cap 10c.

It will be noticed that the use of the cord or 60 cable 12 as carried from the stop 9 to and around the sheave 14 on the stop 10, and thence reversely to be wound upon the spring barrel, is kept taut, the cord being inextensible, although if a slight extension thereof occurs after much use, the 65 screw axis 6 of the drum 7 may be adjusted to take up any slackness. The device thus may be manipulated by one hand, which in practice is more convenient for the operator and a saver of time, as compared with a stop device which includes spring drums at both ends of the shiftable frame bar 5.

My device is of relatively simple and inexpen-

sive construction, and with little or no adjustments, may be mounted operatively upon the dentated bar 5 of any make of typewriting machine or the like.

I claim:

1. A device of the character described, comprising in combination, a shiftable dentated bar, abutments mounted adjacent said bar, releasable marginal stops mounted slidably on the bar for occasional engagements with said abutments, each stop including a resiliently controlled ratchet releasably engaged with teeth of said bar, tension producing means, a cable end-connected thereto, carried thence around a part of the remote stop and reversely returned and end 15 connected to the hither stop, and single reversely rockable operating means for manual manipulation to engage releasably either ratchet in disengaging it from teeth of said bar to permit sliding of the stop to and fro along the bar separately and adjustably.

2. A device of the character described, comprising in combination, a shiftable dentated bar, abutments mounted adjacent said bar, releasable marginal stops mounted slidably on the bar for occasional engagements with said abutments, each stop including a resiliently controlled ratchet releasably engaged with teeth of said bar, a spring drum mounted on one end of said bar, a cable end-connected to and windable 30 on the spring drum, carried thence around a part of the remote stop and returned reversely with its other end connected to the hither stop, and a reversely rockable shaft positioned along said bar, transversely widened and for manual manipulation to rock it in either of opposite directions to releasably engage and actuate either ratchet separately to disengage it from the bar teeth to permit the stop to be slidably adjusted therealong in a to and fro direction relative to the adjust- 40 ments of the other stop.

3. A device of the character described, comprising in combination, a shiftable dentated bar, abutments mounted adjacent said bar, marginal stops mounted slidably on the bar for occasional 45 separate independent releasable engagements with said abutments, each stop including a resiliently controlled ratchet releasably engaged with the bar teeth, a spring drum mounted at one end of said bar, a cable end-connected to and windable on said drum, the remote stop having a sheave thereon, another sheave supported on the hither part of said bar device, the cable being reeved around said sheave and connected to the hither stop, and oppositely rockable means for 50 manually disengaging either stop-ratchet from the bar.

4. In apparatus of the character described, a dentated bar, stop means adjacent thereto, a pair of slide-bodies mounted on said dentated 60 bar having ratchets releasably engaged with detents thereof, resilient means on said slide-bodies bearing on said ratchets to normally retain them in engagement with the detents, a single device, oppositely rockable, and to depress either ratchet 65 to release it from the detented bar, and resiliently controlled single means connected to both slide-bodies and operable when either ratchet is released from the detented bar to tensionally move its connected slide-body separately along the bar.

HAROLD C. FOX.
